CONVERSION OF HYDROCARBONS OF HIGH BOILING POINT INTO THOSE OF LOW BOILING POINT

Ernst Galle, Ludwigshafen-on-the-Rhine, and Walter Rosinsky and Gerhardt Hofmann, Oppau, Germany, assignors to I. G. Farbenindustrie Aktiengesellschaft, Frankfort-on-the-Main, Germany, a Corporation of Germany

No. Drawing. Application August 23, 1928, Serial No. 301,688, and in Germany October 3, 1927

9 Claims. (Cl. 196—54)

This invention relates to the conversion of hydrocarbons of high boiling point range into those of low boiling point range.

We have found that the said conversion of hydrocarbons of high boiling point range is effected, with excellent yields of hydrocarbons of lower boiling point range, by acting upon initial materials of high boiling point range, such as mineral oils, tars, products of the destructive hydrogenation of coal, oils, tars, and the like, or distillation and conversion products of said initial materials, with an addition of catalysts of the type of the complex "ansolvo" acids (Justus Liebig's Annalen der Chemie, vol. 455 (1927), Verlag Chemie G. m. b. H., Berlin, pages 235, 244 and 249) that is to say, compounds or mixtures of organic carboxylic acids with inorganic salts which increase the power of the said organic carboxylic acid to split off hydrogen ions. The said complex "ansolvo" acids contain the inorganic element in complex combination. Complex "ansolvo" acids when added to diazo acetic acid set nitrogen free therefrom and therefore the formation of the complex "ansolvo" acids can be controlled by a simple test; namely the mixture of the said organic carboxylic acids with the said inorganic salts when added to diazo acetic ester must yield a more vigorous evolution of nitrogen, than the individual components separately if complex "ansolvo" acids are formed.

The process is carried out at an elevated temperature, for example, at temperatures ranging between about 350° and 600° C., temperatures between about 400° and 450° C. furnishing particularly good results. The process may be carried out under ordinary or elevated pressure. In some cases it will be advantageous to employ high pressures of about 100, 200 or even 1000 atmospheres, pressures of 100 to 150 atmospheres being very favorable, though in other cases pressures of about 20 or 50 atmospheres may be employed.

The operation may also be conducted in the presence of hydrogen or gases containing or supplying the same.

The following examples will further illustrate the nature of the said invention which however is not limited thereto. The parts are by weight.

Example 1

100 parts of a thin tar fraction boiling at from 200° to 350° centigrade are treated with 5 parts of a double compound of α -naphthoic acid and tin tetrachlorid, at from about 350° to 400° centigrade and under a pressure of about 10 atmospheres. Of the resulting conversion prod-

ucts, 41.2 per cent with reference to the initial material boil below 200° centigrade.

The double compound may also be replaced by the two components, in varying molecular proportions.

Example 2

100 parts of a rectified thick producer tar, 5 parts of a double compound of 1-naphtholcarboxylic acid and aluminium chlorid or the components of the same, as in the preceding example 65 are heated at about 350° to 420° centigrade in an autoclave lined with Monel metal (an alloy containing about 27 per cent of copper, about 65 per cent of nickel and a slight amount of iron). Of the resulting products, 33.5 parts boil below 200° 70 centigrade.

Example 3

100 parts of a thick producer tar, which has been freed from benzine, are treated with three 75 parts of a double compound of oleic acid and zinc chlorid or the components of the same as in Example 1 at about 350° centigrade and 25 atmospheres pressure in an autoclave fitted with stirrers. 35 parts of the resulting products boil below 80 200° centigrade.

Example 4

100 parts of paraffin wax (melting point 41° to 43° centigrade) are heated with 1 part of a double compound of formic acid and aluminium 85 chlorid or the components of the same, as in Example 1 at from about 400° to 440° centigrade and at 330 atmospheres. 99 parts distill over, of which 75 parts boil below 200° centigrade and a further 24 parts boil between 200° and 360° 90 centigrade.

Example 5

100 parts of a mineral oil boiling above 200° centigrade are heated with 5 parts of a double 95 compound of alpha-naphthoic acid and antimony pentachlorid or the components of the same, as in Example 1, under a pressure of 50 atmospheres of hydrogen, up to 420° centigrade. Of the resulting conversion products, 45 parts boil 100 below 200° centigrade.

What we claim is:—

1. In the conversion of hydrocarbons of high boiling point range into others of low boiling point range, the step which comprises acting on 105 the said materials at a cracking temperature with a catalyst of the type of the complex "ansolvo" acids, said "ansolvo" acids or the acid constituent thereof being added to said materials.

2. In the conversion of hydrocarbons of high 110

- boiling point range into others of low boiling point range, the step which comprises acting on the said materials at a cracking temperature with a catalyst of the type of the complex "ansalvo" acids, said "ansalvo" acids or the acid constituent thereof being added to said materials, the process being carried out in the presence of hydrogen. 80
3. In the conversion of hydrocarbons of high boiling point range into others of low boiling point range, the step which comprises acting on the said materials with a catalyst of the type of the complex "ansalvo" acids, said "ansalvo" acids or the acid constituent thereof being added to said materials, the process being carried out at a temperature of between about 350° and 600° C. 85
4. In the conversion of hydrocarbons of high boiling point range into others of low boiling point range, the step which comprises acting on the said materials at a cracking temperature with an added naphthoic acid and aluminium chloride. 90
5. A process for the conversion of tar into hydrocarbons of low boiling point which comprises treating the said initial material under pressure and at about 380° to 420° C. with added 1-naphtholcarboxylic acid and aluminium chloride. 95
6. In the decomposition of hydrocarbons of high boiling point range into others of low boil- 100

- ing point range, the step which comprises acting on the said materials at a temperature of between 400° and 450° C. with a catalyst of the type of the complex "ansalvo" acids, said "ansalvo" acids or the acid constituent thereof being added to said materials. 105
7. In the conversion of hydrocarbons of high boiling point range into others of low boiling point range, the step which comprises acting on the said materials at a temperature of between 350° and 600° C. with an added naphthoic acid and aluminium chloride. 110
8. In the conversion of tars into hydrocarbons of low boiling point range the step which comprises acting on the said materials at a temperature of between 350° and 600° C. with a catalyst of the type of the complex "ansalvo" acids, said "ansalvo" acids or the acid constituent thereof being added to said materials. 115
9. In the conversion of paraffin waxes into hydrocarbons of low boiling point range the step which comprises acting on the said materials at a temperature of between 350° and 600° C. with a catalyst of the type of the complex "ansalvo" acids, said "ansalvo" acids or the acid constituent thereof being added to said materials. 120
